UNITED STATES PATENT OFFICE.

EMORY C. HISCOCK, OF CHICAGO, ILLINOIS, ASSIGNOR TO W. W. KIMBALL COMPANY, OF CHICAGO, ILLINOIS, A CORPORATION OF ILLINOIS.

PNEUMATIC ACTION FOR SELF-PLAYING INSTRUMENTS.

No. 920,744.

Specification of Letters Patent.

Patented May 4, 1909.

Application filed September 25, 1908. Serial No. 454,764.

To all whom it may concern:

Be it known that I, EMORY C. HISCOCK, a citizen of the United States, residing in Chicago, in the county of Cook and State of Illinois, have invented a new and useful Improvement in Pneumatic Actions of Self-Playing Instruments, of which the following is a specification.

This invention relates to the pneumatic actions of self playing instruments, and particularly to the manner of supporting the lifters through which the hammers are operated. In the general construction of these pneumatic actions, it is now necessary when repairing or replacing the lifters or the pneumatics, to disengage or remove a considerable number of the lifters, and in so doing, their adjustment is lost, so that when they are replaced much of the adjustment has to be done over, and generally it is the case that the adjusting devices are numerous and of a kind necessitating considerable work at such times.

My invention is intended to simplify the construction and reduce the number of parts, and also to so support the lifters as to render it easy to get at and remove any one of them without destroying the adjustment of the others.

The nature of the invention is fully disclosed in the description given below, and will be understood from the accompanying drawing, in which latter—

Figure 1 is a partial elevation of an action embodying my invention. Fig. 2 is a section on the line 2—2 of Fig. 1. Fig. 3 shows one of my improved lifters detached. Fig. 4 is a partial horizontal section.

In said drawing, 5 represents the action board supporting the action or striking pneumatics 6. The latter are arranged in several horizontal rows, one above another in the usual manner and the movable side of each of them is provided with a projecting arm 7 having a transverse eye to receive the bent end 8 at the bottom of the lifter 9 to be slipped into it or out from it. The lifters are arranged in vertical positions with their lower ends secured in the eyes of the arms 7, and at the upper end the lifters are provided with bamboo thimbles 10 and 11, firmly secured upon them and provided with felt washers 12 and 13 as seen at Fig. 3. The top thimble and washer rest upon a supporting bar 14 described more particularly below,

and limit the downward movement of the lifters and the lower thimble and washer contact with said bar and limit its upward movement. Between the lower thimbles and the junction with the pneumatics 6, the lifters 6 pass through slots 15 formed in a guide bar 16. The slots 15 are open upon one side as shown so that any lifter can be taken out of it in one direction.

The bar 14 is made in two longitudinal parts 14 and 14^a, the part 14 being held by screws 16 against part 14^a, and the openings therein through which the lifters pass being formed partly in each part of the bar. In consequence of this feature, when it is desired to remove a lifter, it is only necessary to remove or loosen the part 14 of the upper bar, and to disengage the foot of the lifter from the arm 7 of the pneumatic, and the lifter can then be removed. In doing this, the other lifters do not need to be disturbed, because they will be retained in position by the slots of bar 16, but if they do fall out, they can be returned at once to normal positions without any loss of adjustment.

The striker which actuates the key 17 of the instrument is shown at 18, and receives motion from the lifter through a pivoted lever 19 in the usual manner.

I claim—

1. The pneumatic action for self playing instruments wherein are combined a series of pneumatics, a series of vertically arranged lifters for actuating the piano action while playing automatically, and a horizontal longitudinally divided bar between the parts of which bearings are formed for said lifters, one side of the bar being removable, and the lifters being readily and separately detachable from the pneumatics.

2. The pneumatic action for self playing instruments wherein are combined a series of pneumatics, a series of vertically arranged lifters for actuating the piano action while playing automatically, a horizontal longitudinally divided bar between the parts of which bearings are formed for said lifters, and a notched bar 16 staying the lifters between their ends, one side of the divided bar being removable and the lifters being readily and separately detachable from the pneumatics.

EMORY C. HISCOCK.
